UNITED STATES PATENT OFFICE.

ARTHUR E. SNOW, OF ERIE, PENNSYLVANIA, ASSIGNOR, BY MESNE ASSIGNMENTS, TO
U. S. HOFFMAN COMPANY, OF SYRACUSE, NEW YORK, A CORPORATION OF NEW
YORK.

CLOTHES-PRESSING MACHINE.

1,208,714.

Specification of Letters Patent. Patented Dec. 12, 1916.

Application filed July 31, 1912. Serial No. 712,505.

To all whom it may concern:

Be it known that I, ARTHUR E. SNOW, a citizen of the United States, residing at Erie, in the county of Erie and State of Pennsylvania, have invented new and useful Improvements in Clothes-Pressing Machines, of which the following is a specification.

This invention relates to clothes pressing machines and consists in certain improvements in the construction thereof as will be hereinafter fully described and pointed out in the claims.

The purpose of the invention is to provide a machine for pressing garments by supplying heat, moisture and pressure to the garments and at the same time having the machine so arranged that different parts of the garment may be placed in position for operation and the garment suitably stretched or manipulated to accomplish the best results.

The invention is illustrated in the accompanying drawings as follows:

Figure 1 shows a side elevation of the machine, a part of the presser head being in section on the line 1—1 in Fig. 3. Fig. 2 shows an enlarged section of a portion of the buck showing the method of fastening 30 the covering cloth on the buck. Fig. 3 shows a front elevation of the machine, the cover for the coils being in section to better show construction. Fig. 4 shows a section of a detail of the joint connecting the buck to its support. Fig. 5 shows a section on the line 5—5 in Fig. 6. Fig. 6 shows a bottom view of the presser head, one of the plates forming the slotted passage for steam being removed to better show construction. Fig. 7 shows a section on the line 7—7 in Fig. 6. Fig. 8 shows an enlarged view of the flash coil steam generator. Fig. 9 shows an enlarged view of the presser foot for exerting pressure on the head.

1 marks the base or standard on which the presser is mounted. A bracket 2 extends outwardly from this base or standard 1. A table 3 is arranged on the bracket 2 for supporting those parts of the garment that are free from the immediate pressing operation. A cross bracket 4 is mounted on the bracket 2 and supports the buck 5. A presser head 6 is arranged to operate in conjunction with the buck 5. It is carried by the bifurcated arm 7. This arm is pivoted on a pin 8 car-

ried by the yoke 8^a at the top of the standard 1. An extension 7^a extends from the rear of the arm 7 and terminates in a loop or slot 9 (see Fig. 9), the weights 10 being secured to the arm at each side of the slot 9. 60

In the ordinary operation of the machine, the head 6 is pressed against the buck with the garment between the surfaces. In order to change the parts of the garment or different garments, it is desirable that the head 65 be lifted from the buck and swung back out of the way. At the same time, it is desirable that means be provided for exerting pressure on the head so as to give the proper pressure to press the garment. The means 70 for accomplishing this in the present invention comprises a treadle 11 which is pivoted on a pin 12 in the standard 1. An upright 13 is rigidly fixed on the rear end of the treadle 11 by means of rivets 14. A 75 push rod 15 is pivotally secured to the upright 13 by means of a pin 16. The push rod has the shoulder 17 which is adapted to engage the underside of the arm 7^a so as to force the arm 7^a upwardly and the arm 7 downwardly carrying the head into contact with the buck. The push rod has the extension 18 which extends into the slot 9, the said extension contacting the wall of the front end of the slot. A spring 19 ex- 85

Figure 1 shows a side elevation of the machine, a part of the presser head being in section on the line 1—1 in Fig. 3. Fig. 2 shows an enlarged section of a portion of the buck showing the method of fastening 30 the covering cloth on the buck. Fig. 3 shows a front elevation of the machine, the cover for the coils being in section to better show construction. Fig. 4 shows a section of a detail of the joint connecting the buck to its support. Fig. 5 shows a section on the line 5—5 in Fig. 6. Fig. 6 shows a bottom view of the presser head, one of the plates forming the slotted passage for steam being removed to better show construction. Fig. 7 shows a section on the line 7—7 in Fig. 6. Fig. 8 shows an enlarged view of the flash coil steam generator. Fig. 9 shows an enlarged view of the presser foot for exerting pressure on the head.

1 marks the base or standard on which the presser is mounted. A bracket 2 extends outwardly from this base or standard 1. A table 3 is arranged on the bracket 2 for supporting those parts of the garment that are free from the immediate pressing operation. A cross bracket 4 is mounted on the bracket 2 and supports the buck 5. A presser head 6 is arranged to operate in conjunction with the buck 5. It is carried by the bifurcated arm 7. This arm is pivoted on a pin 8 car-

contacts the underside of the arm 7^a and thus exerts pressure on the head. The pressure on the head may be relieved and given a limited movement by a movement of the 5 treadle without releasing the push rod 15 from the arm 7^a. When, however, the treadle 11 is released, the spring 22 draws the pedal end upwardly swinging the arm or upright 18 outwardly and the screw 20 10 coming in contact with the push rod 15 swings the push rod 15 to the rear so as to bring the shoulder 17 out of engagement with the arm 7^a, and the arm 7^a is thus released so that the presser head may be 15 swung upwardly and rearwardly out of the way of the buck.

The presser head is formed of a body 23. A wire gauze 24 is arranged over the face of the head and a cloth 25 stretched over 20 this gauze. Steam is delivered through the body to this face so as to supply the heat and moisture necessary for the pressing. The edges of the cloth are drawn around the edge of the body 23 of the head and secured 25 by a wire 26 which is drawn around the head immediately back of the shoulder 26^a on the body.

A water chamber 27 extends around the edge of the body of the head. This chamber 30 27 is connected by a pipe 28 with an expansion chamber 29. Water is supplied from the supply pipe 30, the supply pipe being connected to the pipe 28 by a T 32 and controlled by a valve 31. The water in 35 the chamber 27 is heated by a gas burner 33. The burner is supported between the brackets 34 extending upwardly from the body 23. It is supplied through a mixer 35 from a flexible gas pipe 36. The burner has 40 the burner openings 37 so directed as to cause the flame to impinge a shoulder 23^a just within that portion of the body 23 in which the chamber 27 is arranged. In this way the water in the chamber 27 is heated. 45 At the same time the water so tempers this heat and so distributes it as to prevent the body of the head taking on an excessive heat, in other words, the water will remain at a temperature somewhat below the boiling 50 point and will so modify and distribute the heat as to maintain the body of the head at an approximately uniform temperature.

In the operation of these machines, it is desirable to have steam delivered through 55 the head to the surface of the head so as to supply the heat and moisture necessary to accomplish the pressing. Heretofore in machines of this type, the steam has been generated outside of the head and delivered to 60 the head by means of boilers maintained for that purpose. In order to have the machine in shape for ready use, it is necessary to maintain the steam on the boiler continuously. Furthermore, the maintenance of 65 steam under these conditions in the hands

of such operators as operate these machines is often dangerous. Such a construction also requires the maintenance of flexible steam joints between the boiler and the head. In the present device, I arrange the generator directly on the head and I also substitute for the boiler a flash boiler so that steam may be delivered almost instantly at any time without the danger and inconvenience of the ordinary boiler.

The generating coil 38 is shown in detail in the enlarged view in Fig. 8. It comprises the entrance pipe 39 which is connected by a header 40 with a second pipe 40^a. The pipe 40^a is connected through the header 41 70 with a pipe 42, the pipe 42 through the header 43 with a pipe 43^a, the pipe 43^a through the header 44 with a pipe 46, the header 44 having the upward turn 45 (see Fig. 3), which carries the pipe 46 above the 75 plane of the main coil. The pipe 46 is connected with the cross pipe 47. The pipe 47 has the downwardly extending pipes 48 at each side of the burner extending to the body 23. The headers of the coil are provided with lugs 38^a and screws 38^b extend through the brackets 34 for securing the coil in place.

It is desirable to distribute the steam over the face of the head so as to give a uniform 80 amount of steam to each portion of the head. The manner of doing this is shown in detail in Figs. 5, 6 and 7. The pipes 48 lead to a manifold chamber 49 arranged in the bottom of the body 23. There are two of these, 85 one for each pipe 48. Passages 50 extend longitudinally of the head from the manifolds 49 and passages 51 extend crosswise from the manifolds 49 connecting said manifolds with the longitudinal passages 52. 90 The distributing passage 50 is connected by feeders 53 with a slot passage 54 and the distributing passage 52 is connected by the feed passages 55 with the slot passages 56. The slot passages 54 and 56 are continued 95 and curved at the ends so as to run into each other.

The face of the body 23 has a depression 57 the peripheral walls of the depression coinciding with the outer edges of the slot 100 passages 54 and 56. The face 58 of the depression is slightly off-set from the plane 105 of the body 23 to permit the insertion of a plate 59, this plate being secured to the face 58 by screws 60. This plate forms one wall 110 of the passages numbered from 50 to 56 and is of a size to form with the walls of the depression 57 slots 61 which extend around the plate. It will be observed that when 115 steam is delivered from the flash coil, it is distributed through these passages referred to entirely around the slot formed by the plate 59 and to the face of the head and that steam is delivered over a sufficient part 120 of the surface to give a substantially uni- 125

form amount of steam to each part of the head. The head being heated through the water system prevents the chilling or condensing of the steam in its passage.

5 The coil 38 is heated by a burner 62, the burner being arranged above the burner 33 and having jet openings 63 to direct the flame upwardly and against the coil. The burner is supplied through the mixer 64 from the gas hose 65.

Water is delivered to the flash coil from the supply pipe 30. The entrance pipe 39 terminates in a controlling valve 66. The controlling valve is connected by a pipe 67 through the T 68 with the pipe 30. The operator having the garment in position desiring steam, opens the valve 66 admitting the water, the water reaching the flash coil is converted into steam and carried to the 15 face of the head. The supply pipe 30 is preferably connected with the water supply through a flexible hose 30^a which permits of the movement of the head.

It is desirable for the purposes of this 25 device to have dry steam. In order to prevent the entraining of water without converting such water into steam through the flash coil I insert into the tubes of the flash coil a plate 69 twisted so as to form a spiral 30 passage in the tube. The steam or water rushing through this passage is thrown through centrifugal force into contact with the walls and in this way all the water is converted into steam.

35 A cover 70 is arranged over the coil 38 and the burners to inclose the flame from the burner and protect the parts. It has suitable openings to permit of the circulation of air for the purpose of combustion.

40 It is desirable to mount the buck so that it will have a limited movement. I accomplish this by providing the buck with downwardly extending brackets 5^a. These extend by the ends of the cross bracket 4. The 45 cross bracket has the perforations 4^a in its ends and the brackets 5^a have the perforations 5^b extending through them. Pins 5^c extend through the perforations 5^b into the perforations 4^a thus forming a pivotal support for the buck. The pins are locked in place by the screws 5^e the ends of the screws extending into annular grooves in the pins 5^c. The pivotal movement of the buck is limited by the screws 4^b which extend upwardly through the bracket 4 against the brackets 5^a.

The buck is provided with a felt 71 over the face of the wood and a cloth 72 stretched over this felt. The edge of the cloth is 60 drawn around the edges of the buck. The buck has the circumferential groove 73. A wire 74 extends around the buck and in this groove, the wire being provided with a tightening device 75. With this device the 65 wire not only holds the cloth but as the

wire is drawn into the groove stretches the cloth thus drawing it evenly into place.

What I claim as new is:—

1. In a clothes pressing machine, the combination of a buck on which a garment 70 can be arranged for pressing; a presser head movably mounted to operate on said buck and having steam passages extending through its face; a flash steam coil carried by the head and connected at a discharge 75 end with said passage; a gas burner carried by the head arranged to heat said coil; means for supplying combustible mixture to said burner; and means for supplying water to the opposite end of the coil from the 80 discharge.

2. In a clothes pressing machine, the combination of a buck on which a garment can be arranged to be pressed; a presser head movably mounted to operate on said 85 buck and having steam passages extending through its face; means for supplying steam to said passages; a hot water system carried by said head for heating the body adjacent to the face of said head; and means for 90 heating the water of said system.

3. In a clothes pressing machine, the combination of a buck on which a garment can be arranged to be pressed; a presser head movably mounted to operate on said 95 buck and having hot water heating passages carried thereby adjacent to the face of the head; and means carried by the head for heating the water in said passages.

4. In a clothes pressing machine, the combination of a buck on which a garment can be arranged to be pressed; a presser head movably mounted to operate on said buck and having hot water heating passages carried thereby adjacent to the face of the head; 100 means carried by the head for heating the water in said passages; and means for supplying steam to the face of said head.

5. In a clothes pressing machine, the combination of a buck on which a garment can be arranged to be pressed; a presser head movably mounted to operate on said buck and having steam passages extending through its face and water passages adapted to heat the head; a generator carried by the head 110 for generating steam; a connection between the generator and said steam passages; means carried by the head for heating the generator; and means carried by the head 115 for heating the water in the hot water passages.

6. In a clothes pressing machine, the combination of a buck on which a garment can be arranged to be pressed; a head having a body with an annular water chamber along 125 its periphery adjacent to the face of the head; and an expansion chamber connected with said water chamber.

7. In a clothes pressing machine, the combination of a buck on which a garment can 130

be arranged to be pressed; a head having a body with an annular water chamber along its periphery adjacent to the face of the head; an expansion chamber connected with 5 said water chamber; and a gas burner having its flames directed downwardly against the body of the head adjacent to said water chamber.

8. In a clothes pressing machine, the combination of a buck on which a garment can be arranged to be pressed; a presser head movably mounted to operate on said buck, said head having a depression in its face; a plate mounted in said depression forming 10 with the walls of the depression a steam slot, said head having steam distributing 15 passages for distributing steam to the face of said head; and means for supplying steam to said passages.
9. In a clothes pressing machine, the combination of a buck on which a garment can be arranged to be pressed; a presser head movably mounted to operate on said buck, said presser head having in its face a depression and having slot passages and adjacent distributing passages with feed 20 passages connecting said distributing passages with the slot passages; manifolds for carrying steam to the distributing passages; a 25 plate arranged in said depression and forming at its edge a slot connected with the slot passages; a steam generator; and a connection between the generator and the manifolds.
10. In a clothes pressing machine, the combination of a buck on which a garment can 30

be arranged to be pressed; a presser head movably mounted to operate on said buck, 40 said head being provided with a plurality of depressions in its face; plates arranged in said depressions and forming at their edges in conjunction with the walls of the depressions peripheral slots leading to the face of the presser head; and means for delivering steam to said slots.

11. In a clothes pressing machine, the combination of a buck; a pivotal mounting for the buck, said pivot having a horizontal axis; and a presser head swinging on an axis parallel to the axis of the pivotal mounting of the buck operating in connection with the buck.

12. In a clothes pressing machine, the combination of a presser head pivotally mounted; a buck; a pivotal mounting for the buck, 55 said mounting having a horizontal axis parallel to the axis of the pivot on which the presser head swings, said pivotal mounting comprising a standard bracket having perforations; ears extending downwardly from 60 the buck and overlapping the standard bracket, said ears having perforations; pins extending into said perforations, said pins having grooves therein; and locking pins extending into said grooves.

In testimony whereof I have hereunto set my hand in the presence of two subscribing witnesses.

ARTHUR E. SNOW.
